(57) **CLAIM**

The ornamental design for an osteotomy wedge, as shown and described.

DESCRIPTION

FIG. 1 is a perspective view of an osteotomy wedge comprising the new design;

FIG. 2 is front side view thereof;

FIG. 3 is a back side view thereof;

FIG. 4 is a left side view thereof;

FIG. 5 is a right side view thereof;

FIG. 6 is a top view thereof; and,

FIG. 7 is a bottom view thereof.

The broken lines depict portions of the osteotomy wedge that form no part of the claimed design.
